UNITED STATES PATENT OFFICE.

FERGUS F. WILSON, OF BROOKLYN, NEW YORK, ASSIGNOR TO MERGENTHALER LINOTYPE COMPANY, A CORPORATION OF NEW YORK.

TYPOGRAPHICAL MACHINE.

1,115,141.

Specification of Letters Patent. Patented Oct. 27, 1914.

Application filed October 11, 1912. Serial No. 725,115.

To all whom it may concern:

Be it known that I, FERGUS F. WILSON, a citizen of the United States, and a resident of Brooklyn, county of Kings, and State of New York, have invented a new and useful Improvement in Typographical Machines, of which the following is a specification.

My invention relates to typographical machines, such as linotype machines of the general character disclosed in Letters Patent of the United States to O. Mergenthaler, No. 436,532, wherein are presented a mold and other casting devices co-operating therewith, designed to produce a printing bar or slug, having a body formed with the printing characters thereon.

More particularly, it relates to the production of bars provided with overhanging portions carrying printing characters, which portions normally project over and rest upon adjoining slugs or bars, for instance, such as are disclosed in my application for Letters Patent, Serial No. 693,602, filed April 27, 1912.

The application referred to shows ordinary slugs of the usual thickness, and co-operating slugs with a more reduced or thinner body, which construction of the latter slug is rendered possible by the fact that its main purpose is to provide the projecting characters, which are supported in use by the other slug. In order to give the overhanging portions greater rigidity, they are preferably formed with underlying strengthening elements, which elements project from the side of the slug and below the edge thereof. To produce slugs of this description, I preferably employ a slotted mold formed on its face or front surface with transverse cavities communicating with the mold slot, and in combination therewith, a matrix formed with cavities registering with those on the mold, in such manner that the overhanging portions of the slug are formed partly in the mold and partly in the matrix.

In the accompanying drawing, I have shown my invention in preferred form and by way of example, and as applied to the Mergenthaler linotype machine, but obviously many variations and modifications therein, and in its mode of application, are possible without departure from its spirit; and generally speaking, I desire it to be understood that I do not limit myself to any

specific form or embodiment except in so far as such limitations are specified in the claims.

In the accompanying drawing: Figure 1 is a transverse section through the mold, etc., of a linotype machine; Fig. 2 is a perspective, partly in section, of the matrix; Fig. 3 is a perspective, partly in section, of the mold; Fig. 4 is a perspective of two co-operating slugs separated from each other; and Fig. 5 is a similar perspective, on an enlarged scale, of several slugs in operative relation to each other.

As in my previous application, the slug A is formed with overhanging portions, each comprising a printing element a and a strengthening element a' beneath it, which portions project over and rest upon the edge of the ordinary slug B between the type or characters b formed thereon (see Figs. 4 and 5). The devices herein shown and now to be described are designed to produce a slug of this description.

In Fig. 2, is illustrated a matrix-block X, carrying the strip R, which may be formed with any desired kind of matrix character, such for instance as the continuous depression R' intended to produce a horizontal line. This depression normally registers with the mold slot and forms the printing ridge c on the slug A. The strip R is also formed with a plurality of transverse depressions S, S, communicating with the depression R' and extending longitudinally therefrom. These depressions S, S, form the upper or printing elements a, a, on the slug A. The other elements of the projecting portions, namely, the under or strengthening elements a', a', are formed by the transverse recesses or cavities Q, Q, formed in and below the face or front surface of the mold L and communicating with the mold slot P and extending therefrom substantially in a perpendicular plane. The depressions S, S, of the matrix are so located and proportioned as to correspond and register with the cavities Q, Q, of the mold, during the casting operation.

Fig. 1 illustrates the several parts in operative position, when my invention is employed in connection with the ordinary linotype machine. The block X, carrying the matrix strip R, is held by the first elevator M in operative relation to the mold L carried by the mold wheel N, and the molten

metal is delivered to the mold slot P from the pot-mouth O, all in the ordinary manner. This operation results in the production of the slug A, the body thereof being formed in the mold slot P, the printing ridge e by the longitudinal depression R of the matrix, and the projecting portions by the coöoperating and registering matrix depressions S, S, and mold cavities Q, Q, the former producing the ruling or printing elements a, a, and the latter the underlying or strengthening elements a', a'. As will be readily understood by those skilled in the art, and in order to adapt the mold to general use, the cavities Q, Q, may be formed in a removable section T detachably secured to the mold L.

As previously stated, I have shown my invention simply in approved form and by way of example, but obviously many variations and modifications thereof, and in its mode of application to other typographical casting machines, will suggest themselves to those skilled in the art and still be comprised within its scope.

Having thus described my invention, its construction and mode of operation, what I claim and desire to secure by Letters Patent of the United States is as follows:

- 30 1. A slotted mold formed in its front surface with transverse cavities communicating with the mold slot and extending therefrom substantially in a perpendicular plane, so as to produce a slug with overhanging character bearing portions on its edge adapted to overhang an adjacent member, which portions are cast in said cavities.
- 35 2. A slotted mold provided with a removable section formed with transverse cavities communicating with the mold slot and ex-

tending therefrom substantially in a perpendicular plane, so as to produce a slug with overhanging character bearing portions adapted to overhang an adjacent member, which portions are cast in said cavities. 45

3. A slotted mold formed with transverse cavities located in and below its front surface and communicating with the mold slot and extending therefrom substantially in a perpendicular plane, so as to produce a slug 50 with reinforced overhanging character bearing portions adapted to overhang an adjacent member, which portions are cast in said cavities.

4. A slotted mold formed with transverse 55 cavities formed in its front surface and communicating with the mold slot and extending therefrom substantially in a perpendicular plane, in combination with a matrix formed with cavities registering 60 with those on the mold; whereby a slug is produced with overhanging character bearing portions which are formed partly in the mold and partly in the matrix.

5. A slotted mold formed with a trans- 65 verse cavity in its front surface and communicating with the mold slot and extending therefrom substantially in a perpendicular plane, in combination with a matrix having a depression registering with said cavity; 70 whereby a slug is produced with a reinforced overhanging character bearing portion.

In testimony whereof I hereunto set my hand this ninth day of October, 1912, in the 75 presence of two attesting witnesses.

FERGUS F. WILSON.
